UNITED STATES PATENT OFFICE

163,610

CLOCKCASE

Alan E. Koplar, Chicago, Ill.

Application March 3, 1951, Serial No. 14,375

Term of patent 7 years

(Cl. D42—7)

To all whom it may concern:

Be it known that I, Alan E. Koplar, a citizen of the United States and a resident of Chicago, in the county of Cook and State of Illinois, have invented a new, original, and ornamental Design for a Clockcase, of which the following is a specification, reference being had to the accompanying drawing, forming part thereof.

In the drawing:

Figure 1 is a front elevational view of a clockcase, showing my new design; Fig. 2 is a top plan view of said clockcase; and Fig. 3 is an end elevational view of said clockcase.

I claim:

The ornamental design for a clockcase, as shown.

ALAN E. KOPLAR.
